FIG. 1.

FIG. 2.

FIG.

Inventor

Emil Gathmann

By his Atty. Baldwin Wright

UNITED STATES PATENT OFFICE.

EMIL GATHMANN, OF BALTIMORE, MARYLAND.

INGOT-MOLD.

1,188,751.

Specification of Letters Patent. Patented June 27, 1916.

Application filed May 6, 1916. Serial No. 95,878.

To all whom it may concern:

Be it known that I, EMIL GATHMANN, a citizen of the United States, residing in Baltimore, Maryland, have invented certain new and useful Improvements in Ingot-Molds, of which the following is a specification.

This invention relates to certain improvements in the construction of ingot molds 10 of the class in which the larger part of the mold is uppermost. Molds of this kind are generally open at both top and bottom, the bottom being closed while casting by means of a stool on which the mold rests 15 and which is sometimes provided with a short projection which enters the opening in the bottom of the mold.

The object of my present invention is to 20 efficiently seal the bottom portion of the mold chamber in such manner as to prevent the escape of the molten metal therefrom and to also so shape or form the lower portion of the mold chamber that a relatively small crop of the lower or butt end of the 25 ingot is required and the presence or formation of reentrant angles, which would impede the stripping of the ingot from the mold, is prevented.

In this class of molds, known as "big- 30 end-up" molds, where the mold is solid or not made in sections as is sometimes done, the ingot is stripped from the mold by either being raised or pushed out of the mold, or the mold is reversed and the ingot 35 dropped out. If the molten metal leaks from the bottom of the mold in such a manner as to form a lateral fin at the inner end of the ingot, the stripping of the ingot is prevented or impeded, furthermore if the 40 walls of the mold cavity are not properly formed what are known as "stickers" are formed on the ingot which prevent or impede the stripping operation. It is quite important that the mold cavity should be 45 free from reentrant angles which tend to impede the stripping operation.

According to my present invention the bottom opening of the mold is preferably formed with walls which converge down- 50 wardly and the walls of the lower portion of the mold cavity are formed with rounded or convex walls surrounding the inner end of the bottom opening and which merge into the concaved walls of the lower portion 55 of the mold. By this construction the presence or formation of reentrant angles

is prevented and the stripping of the ingot is facilitated. Where the mold stool is provided with a projection which enters the bottom opening in the mold such projection is preferably tapered inwardly and sealing material of a refractory nature is spread upon the top of the stool and this material also enters the recess surrounding the inwardly projecting portion of the stool. In some cases the projection on the stool may be dispensed with and the refractory material is made to fill or partially fill the bottom opening of the mold.

In the accompanying drawings, Figure 1 70 shows a vertical central section through an ingot mold embodying my improvements. Fig. 2 is a view on an enlarged scale and in vertical section of the lower portion of the mold. Fig. 3 is a view dissimilar to Fig. 75 2 of a modification.

The mold A may be of usual construction but is preferably of the kind shown, i. e., a big-end-up mold having its walls thicker in the lower portion than in the upper portion thereof for purposes now well understood. Devices *a* may be attached to the mold to which the mold-lifting mechanism may be applied, and the mold may be provided with a sink-head or feeder B comprising a metallic shell *b* and a lining *b'* of suitable material, such as loam. The stool C, shown in Figs. 1 and 2, has an inwardly projecting portion *c* which is preferably tapered inwardly as shown.

The formation of the mold cavity in its lower portion is of great importance and my invention relates to that part of the mold. In the three figures of the drawings the lower portion of the mold cavity 95 is shown as being necked-in toward the bottom opening of the mold and this necked-in portion is curved or concaved, the radius of the concave being preferably less than one-half the diameter of the mold 100 at its lower portion. This is indicated at *a'*. The walls of the bottom opening of the mold may be flat or straight as shown, but preferably tapering outwardly as indicated. Where the walls of the bottom opening join the concaved walls *a'* there is a rounded portion *x*, the radius being, as indicated in the drawings, relatively short being struck from the centers *y*. In this way the concaved walls gradually merge 110 into the tapered walls of the bottom opening of the mold and the sticking of the ingot

in the mold at its lower end is entirely prevented.

If the portion α were angular the molten metal would be apt to cut into the mold 5 walls and form a recess or recesses where the metal would enter and thus form keys or stickers which would impede the stripping operation. Furthermore by reason of the form which I give to the lower portion 10 of the mold, the molten metal, while being poured, will spread sidewise against the concave portions α' and will be directed upward and thus lessen the liability of forming stickers. It is also apparent that 15 even should the walls α' be worn away during the pouring of the molten metal the formation of stickers or reentrant angles will not occur.

As before stated the radius of the concave α' is preferably less than one-half the diameter of the mold cavity in its lower portion. This is for the reason that after 20 the ingot is formed it is customary to reheat it preliminary to the rolling operation and at this time some of the coke which usually 25 forms the bed upon which the ingot rests will adhere to the lower portion of the ingot and such adhering coke is subsequently 30 rolled into the metal when the ingot is being reduced to the desired diameter of bloom or billet unless it is cropped. It is therefore desirable to give to the lower end 35 of the mold a curvature of minimum radius consistent with the ease of extraction of the ingot from the mold so that the amount of metal necessary to crop from the bottom of the ingot to remove the coke-impregnated part thereof may be as small as possible.

In order to seal the bottom opening suitable 40 sealing material, such as firebrick or loam baked hard in the mold itself, or otherwise applied, is spread upon the projection ϵ as indicated at D in Figs. 1 and 2, or is made to fill or partially fill the bottom 45 opening as indicated at D' in Fig. 3. This

sealing material may, if desired, be protected in the manner described in my Patent No. 1,170,629 of February 8, 1916, but my invention does not relate to this feature but is concerned with a particular way of 50 forming the lower portion of the mold cavity which is not shown in said prior patent.

I claim as my invention:

1. A metallic mold, the cavity of which 55 in its lower portion has concaved walls, and which mold has a bottom opening formed with walls which converge downwardly and with rounded or convex walls surrounding the inner end of said opening 60 which merge into the concaved walls of the lower portion of the mold.

2. A metallic mold, the cavity of which in its lower portion has concaved walls, and which mold has a bottom opening 65 formed with walls which converge downwardly and with rounded or convex walls surrounding the inner end of said opening which merge into the concaved walls of the lower portion of the mold, and sealing material applied in the bottom opening of the mold.

3. A metallic mold, the lower portion of which has concaved walls and which mold has a bottom opening surrounded at its 75 inner end with rounded or convex walls which merge with the concaved walls of the lower portion of the mold.

4. A metal mold open at top and bottom and the lower portion of which surrounding the bottom opening has concave walls, the radius of which is less than one-half the diameter of the lower portion of the mold cavity.

In testimony whereof, I have hereunto 85 subscribed my name.

EMIL GATHMANN.
